No. 36,993.

Patented June 21, 1904.

UNITED STATES PATENT OFFICE.

FRANCIS J. TORRANCE, OF ALLEGHENY, AND JOHN F. WHITEHEAD, OF
NEW BRIGHTON, PENNSYLVANIA.

DESIGN FOR A LAVATORY.

SPECIFICATION forming part of Design No. 36,993, dated June 21, 1904.

Application filed November 17, 1902. Serial No. 131,785. Term of patent 14 years.

To all whom it may concern:

Be it known that we, FRANCIS J. TORRANCE, residing at Allegheny, Allegheny county, and JOHN F. WHITEHEAD, residing at New Brighton, Beaver county, Pennsylvania, citizens of the United States, have invented a new, original, and ornamental Design for Lavatories.

The figure shown is a perspective view of the lavatory.

What we claim, and desire to secure by Letters Patent, is—

The ornamental design for a lavatory herein shown.

FRANCIS J. TORRANCE.
J. F. WHITEHEAD.
